United States Patent Office.

THE RON WEBB, OF BUDA, ILLINOIS.

Letters Patent No. 85,878, dated January 12, 1869.

IMPROVEMENT IN BEE-HIVES.

The Schedule referred to in these Letters Patent and making part of the same.

To all whom it may concern:

Be it known that I, THERON WEBB, of Buda, in the county of Bureau, and in the State of Illinois, have invented certain new and useful Improvements in Bee-Hives; and do hereby declare that the following is a full, clear, and exact description thereof, reference being had to the accompanying drawings, and to the letters of reference marked thereon.

The nature of my invention consists in the construction and general arrangement of a bee-hive, which will be hereinafter more fully set forth.

In order to enable others skilled in the art to make and use my invention, I will now proceed to describe its construction and operation, referring to the annexed drawings, which form a part of this specification, and in which—

Figure 1 is a side elevation, in section;

Figure 2 is a sectional front elevation; and

Figure 3 is a perspective of the slides used to cover or close the entrances to the hive.

The lower part of the hive consists of a box, A, in the front and at the base of which is cut the entrance a, for the bees. This entrance may be closed by means of a sliding door, B, which is placed at the front of the box A, and which, when raised to leave the entrance open, is retained in its position by means of a small spring, O, as shown in fig. 1.

The slide B, closing the entrance to the hive, is perforated parallel to and near its lower margin, thereby affording ventilation when the slide is placed over the entrance a.

Above the entrance a, on the outside of the box A, is placed a projection or cap, A', which serves to protect the entrance from rain, &c.

In the rear side of box A, is a small hole, D', with a swinging slide, E, this hole being protected by wire gauze, placed on the inner side, and serves to ventilate the hive, at will.

The upper edges of the front and back parts of box A are made with a shoulder, b, on the inside, upon which shoulder rest the ends of the upper cross-bars of the frames D D, which frames may be of any number desired.

The frame D is constructed of a top bar, c, bottom bar d, and side bars e e, and is of such size as to allow the bees to pass all around the frame D, between it and the top, bottom, and sides of the box A.

On the inner side of the two side bars e e, and extending the whole length of the same, are secured strips i i, bevelled so as to form a wedge-edge.

The under side of the top bar c is provided with three bevelled strips, f f, running parallel with each other, and extending to the side bars e e on both sides, the middle one connecting and forming a joint with the strips i i on said side bars.

The advantage of the three bevelled strips f f is that they afford the bees a firmer foundation upon

which to build their comb than could be secured by a single strip, thereby diminishing the liability of the comb to break or melt from its foundation in warm weather.

The middle one of the three bevelled strips, f f, is more prominent than the outside ones, and the base of the latter do not extend to the edges of the top bar c, but are placed a suitable distance from the same.

The upper side of the top bar c, of the frame D, is of convex form from the top to the outer edges, thereby preventing the different frames from becoming firmly stuck together with the comb.

In the centre of the top bar c, and on its upper side I place a pin, k, for the convenience of handling the frames.

A platform, F, rests upon and covers the box A forming the floor of the second compartment or box, G. Through this floor, and near the corners of the same, are four holes, g g, opening into two honey-boxes H H which are placed on platform F, and directly over the holes, each of said holes being provided with a slide or shut-off, h, to prevent the bees from passing into the boxes H H, when not desired.

The honey-boxes H H are of rectangular form, without bottom, placed at the sides of the box G, occupying the whole length of the same, from front to rear, leaving an open space between them and the centre, and have, at one end, a sliding door, to open or close the same, at will.

Through the platform or floor F, at its front edge is cut an aperture or opening, m, over which is placed a funnel, I, which passes through the top of the box G, and into the feed-box J, conducting the bees thereto.

A slide, K, rests upon the floor F, and passes through the back part of the funnel I, to the front part thereof, closing the aperture m, for the purpose of shutting off the bees from the feed-box J; the slide K being furnished with a long handle, M, which rests upon and extends across the floor F, and passes out through the rear side of box G, said slide being made to work thereby passing under two cleats n n, which are secured to the floor F.

The front side of the box G is provided with an opening, o, opposite to and corresponding in size with the opening m, already described, and this opening is constantly covered by a perforated slide, p, except when it is desired to hive the bees, when a metal slide, S, is inserted through said opening o, and completely closes the aperture m, from the lower side, shown in fig. 1.

On the floor of feed-box J is placed a trough, or other suitable vessel, N, to contain the feed.

The sides of the boxes G and J are furnished with ventilators, O O, protected by wire gauze, on the inside, and those in the box G have sliding covers on the outside, as shown in fig. 2.

onto the upper edges, and covering the whole upper part of the feed-box J, is inserted a pane of glass, R, thereby giving the bees the benefit of the light and when required.

The feed-box J is covered by a hinged lid, P, which can be opened or closed at pleasure.

Having thus fully described my invention, What I claim as new, and desire to secure by Letters Patent, is—

1. The combination of the box or main hive A, containing the frames D D, the box G, enclosing the honey-boxes H H, and the feed-box J, covered by glass plate R, and hinged lid P, all constructed and arranged substantially as and for the purposes herein forth.

2. The frame D, when constructed as described, with

the top bar, of a convex form on its upper side, and when provided with wedge-shaped strips *i i*, on the side bars, and with three horizontal wedge-shaped strips *f f*, on the lower side of the top bar, the centre one of the said strips *f f* forming a joint with the side strips *i i*, substantially as and for the purposes herein described.

3. The arrangement of the main hive A, platform F, aperture *m*, slide K, funnel L, and feed-box J, all substantially as herein shown and described.

In testimony that I claim the foregoing, I have hereunto set my hand, this 27th day of October, 1868.

HERON WEBB.
